UNITED STATES PATENT OFFICE.

FRED F. MAIN, OF CHICAGO, ILLINOIS, ASSIGNOR TO JOHN T. UNDERWOOD, OF BROOKLYN, NEW YORK.

TYPE-WRITING MACHINE.

1,055,480.

Specification of Letters Patent.

Patented Mar. 11, 1913.

Application filed February 25, 1911. Serial No. 610,716.

To all whom it may concern:

Be it known that I, FRED F. MAIN, a citizen of the United States, residing in Chicago, in the county of Cook and State of Illinois, have invented certain new and useful Improvements in Type-Writing Machines, of which the following is a specification.

This invention relates to means for 10 turning the carriage of a typewriting machine, to begin a new line of writing.

The object of the invention is to provide simple and efficient means for this purpose, and for automatically line-spacing the 15 paper.

I connect to the carriage the piston of a pneumatic cylinder, and I provide a finger-piece or key for opening the valve to admit air to said cylinder and to operate the piston and return the carriage; the air pressure being continued as long as said key remains depressed. An improved connection is made between the piston rod and the line-spacing mechanism of the typewriter for turning 25 the platen when the carriage is run back.

In the accompanying drawings, Figure 1 is a side elevation of an Underwood front strike writing machine provided with the present improvements. Fig. 2 is a sectional view of a three-way valve connected to the pneumatic cylinder, and showing the valve closed against admission of compressed air. Fig. 3 is a similar view showing the valve open. Fig. 4 is a perspective view showing 30 the front left hand corner of the paper carriage and a part of the automatic platen rotating means. Fig. 5 is a rear view of the machine, and Fig. 6 is an elevation illustrating the method of operating the line-spacing lever.

As usual in said machine, key levers 1 operate bell cranks 2 to throw type bars 3 up to strike a platen 4, which is mounted on a carriage 5. This carriage is driven by 45 a spring-barrel 6, and controlled by escapement mechanism 7 operated by universal bar 8, which in turn is operated by the type bars 3.

When the line is completed, and it is desired to return the carriage to begin a new line, the operator depresses a lever or key 9, which is provided at the front of the keyboard, and extends upwardly from a rock shaft 10, which extends horizontally back, and at its rear end is provided with an up-

standing rock arm 11, this being swung to the right at Fig. 5 when the key 9 is depressed. To the upper end of said rock-arm 11 is connected a link 12, the other end of which is attached to an arm 13 fixed to a 60 three-way valve 14. When said key is depressed, as aforesaid, the arm 13 is thrust from the position at Fig. 2 to that at Fig. 3, and a central perforation or passage in said valve is opened to admit air through an inlet 65 or pipe 16, which is connected to any source of supply 17 of compressed air. The air is thus admitted to a cylinder 18, in which plays a piston 19 having a rod 20, which at Fig. 5 projects to the left from said cylinder 70 18, and is attached by means of a nut 21 and eye 22 to a rod 23, which extends back along the cylinder 18 and is connected to the carriage 5 of the typewriter to move the same to the left at Fig. 5, which is a 75 rear view; such movement to the left throwing the carriage back to the beginning of a new line.

The rod 23 is not connected directly to the carriage, but to the line-spacing devices, 80 so that the latter are automatically operated by the piston 19. These connections include a rock-arm 24 extending upwardly from a horizontal rock shaft 25, which extends from the rear to the front of the carriage, and at 85 its forward end carries an upright rock-arm 26, to engage a lever 27 fulcrumed at 28 on the carriage 5, and constituting the usual line-spacing lever of said Underwood type-writing machine, said lever being adapted 90 to drive a pawl 29 which meshes with a ratchet 30 secured to the platen 4. At the depression of said key 9 therefore, the arm 11 is rocked and the valve 14 is opened, the air is admitted to the cylinder, and the piston is thrust back and by means of the rod 23 rocks the rock shaft 25 and the arm 26, and swings the lever 27 to turn the ratchet 30 and platen 4. Pressure upon the piston 19 is sufficient not only to rock the line-space lever and turn the platen, but also to thrust the entire carriage to the left as far as it will go at Fig. 5, so that the same is brought to position to begin a new line of writing.

The operator holds down the key 9 until the carriage has completed its return movement and then releases the same; a spring 31 connected to the arm 13 returning the latter to normal position together with the 110

valve 14 and key 9; this movement of the valve serving to connect the passage 15 therein with a vent 32 in the valve case, at the same time that said passage is put into communication through a branch 33 with the interior of the cylinder 18, so as to exhaust the same, as seen at Fig. 2.

It will be seen that the operator can use this device for returning the carriage either 10 all the length of its run, or only part way, as desired; and after a little practice, he can succeed in landing the carriage at any desired place on the line of its return movement, which is a desideratum.

15 A spring 34, here shown as attached to the eye 22 of rod 23, draws back the piston 19 and rod 23 to release the line space mechanism from said rod when the pressure is released in the cylinder 18.

20 Having thus described my invention, I claim:

1. In a typewriting machine, the combination with a letter-feeding carriage, of a key-operated carriage-returning device comprising a pneumatic cylinder and a piston therein, a rod connected to said piston, and line-spacing devices on the carriage operated by said rod with the return of the carriage effected through said rod, said rod being 25 connected at one end to the piston, and at the other end to a rock arm provided upon a rock shaft, the latter also carrying an arm to engage with the usual line-spacing lever of said carriage.

35 2. In a typewriting machine, the combination with a traveling carriage having a rotatable platen therein, of a line-space mechanism for said platen having a lever extending to the front of the machine, means 40 for drawing forward the carriage in letter-feeding direction, a pneumatically driven piston at the rear of the machine, a rock shaft extending from said line-space lever to the rear of the carriage, a link connecting said piston to said rock shaft to move said line-space lever and return said carriage, and a spring drawing said link to free said line-space lever.

3. In a typewriting machine, the combination with a carriage having a rotatable platen therein, of a line-space mechanism for said platen comprising a spring normally holding it set, means for feeding the carriage in letter-feeding direction, a pneumatically driven piston arranged to operate 50 said line-space mechanism and return said carriage, a key controlled valve admitting air to drive said piston and releasing said

air on the release of said key, and a spring positively moving said piston to release said 60 line-space mechanism from it when said air is released.

4. In a typewriting machine, the combination with a traveling carriage having a rotatable platen therein, of a manually operable line-space mechanism for said platen, means for feeding the carriage in letter-feeding direction, a pneumatically driven piston arranged to first operate said line-space mechanism and then return said carriage, a key-operated valve admitting air to said piston and releasing said air on the release of said key, and means for positively freeing said line-space mechanism from said piston on the release of said key.

5. In a typewriting machine, the combination with a letter-feeding carriage having a platen, of a line-space mechanism for said platen including a lever extending to the front of the machine for optional manual 80 operation, a pneumatically-driven piston at the rear of the machine, a rock shaft extending from said line-space lever to the rear of the carriage, and a link connecting said piston to said rock shaft to enable the piston to operate the line-space mechanism; said piston connected through said line-spacing mechanism to the carriage to return the latter.

6. In a typewriting machine, the combination with a letter-feeding carriage having a platen, of a line-space mechanism for said platen including a lever extending to the front of the machine for optional manual operation, a pneumatically-driven piston, and a train of mechanism wholly on 90 said carriage and extending to said piston for connecting said piston to said line-space mechanism to operate the latter and concomitantly return the carriage.

7. In a typewriting machine, the combination with a letter-feeding carriage having a platen, of a line-space mechanism for said platen including a lever for optional manual operation, a pneumatically driven piston, a connection extending from said line-space lever to the rear of the carriage, and means connecting said piston to said connection to enable the piston to operate the line-space mechanism; said piston operating 105 to return the carriage concomitantly with the operation of said line-space mechanism.
